DISPLAY RACK

John Oster, Racine, Wis., assignor to John Oster
Manufacturing Co., Racine, Wis., a corporation
of Wisconsin

Application April 6, 1935, Serial No. 14,989

2 Claims. (Cl. 248—300)

This invention relates to a display rack for hair clippers or similar articles although it is particularly designed and adapted for use in displaying hand hair clippers.

5 One of the objects of the invention is to provide a display rack of this character which prominently and attractively displays the clippers in a natural fashion and in such manner that the holders which support the clippers are effectively 10 concealed so that the observer will, practically speaking, see only the clippers. Thus, the display of the clippers is not detracted from by the holders and the observer will not have his 15 attention diverted by the holders.

15 Another object of the invention is to provide a display rack of this character which displays a plurality of clippers of different styles or sizes on one board and at the same time and displays each clipper in a position in which it is often 20 ordinarily seen in use.

25 A still further and important object is to provide a display rack having holders with which the clippers are releasably interlocked. Preferably, this interlock is effected under the influence 30 of the spring embodied in the clipper itself so that the clipper may be put into the rack or taken therefrom by gripping the handles of the clipper in the normal way, pressing them toward each other and then sliding the cutting head of 35 the clipper into or out of the holder.

Another object of the invention is to provide a display rack having these advantages and capacities and which is very simple and durable in its construction, susceptible of economic production and yet highly effective in use.

40 Other objects and advantages reside in certain novel features of the construction, arrangement and combination of parts which will be hereinafter more fully described and particularly pointed out in the appended claims, reference being had to the accompanying drawings forming a part of this specification, and in which:

45 Figure 1 is a view in top plan showing a display rack embodying the invention but illustrating only one hair clipper supported in the rack;

Figure 2 is a view in cross section taken on line 2—2 of Figure 1, parts being shown in elevation for the sake of simplicity in illustration;

50 Figure 3 is a view in cross section taken on line 3—3 of Figure 2, parts being shown in elevation for the sake of illustration; and

55 Figure 4 is a fragmentary view partly in top plan and with parts broken away and shown in horizontal section to further illustrate how a

clipper is engaged and held in its clipper holder.

Referring to the drawings, the numeral 1 designates a display board which may be suitably covered, as indicated at 2, and also appropriately ornamented as well as having suitable advertising matter applied to its exposed surface. To the upper surface of the board a plurality of clipper holders, designated at 3, 4, 5, 6, 7, and 8, are secured. These holders are of identical construction but they are disposed on the display board in spaced rows, the holders 3, 4, and 5 making up one row and the holders 6, 7, and 8 another row. Preferably, the holders of one row are aligned with the holders of the other.

Each clipper holder comprises a metal bracket arm designated generally at 10 and having an attaching portion 11 riveted or otherwise suitably secured as at 12 to the board. Each bracket arm also has an outwardly angled portion 13, to the outer end of which a clipper holder bracket of metal and designated generally at 14 is secured. Each bracket 14 has a strip-like body portion 15, the center of which is secured, for example, by spot welding to the outer end of the angled portion 13 of its bracket arm. The ends of the strip-like body portion have angular lugs 16 and 17 integral therewith and overhanging the ends of the body portion so that the brackets 14 provide what may be regarded as fixed generally C-shaped clamps.

30 This type of display rack is designed for especially advantageous use with hand hair clippers of the type designated generally at C. These clippers usually comprise a cutting head having a fixed blade 20 and a reciprocable blade 21, the blade assembly being suitably interconnected with a housing 22. A fixed handle 23 is integral with the housing 22 while the movable handle of the clipper designated at 24 has a bearing 25 rotatable about a bearing member 26 provided therefor in the housing. This movable handle also has a driving arm 27 which interengages with the blade 21. A spring 28 is interconnected with the housing and the movable handle in the conventional manner so as to tend to spread the handles 23 and 24 and thereby move the clippers to one position. When the handles are pulled together the movable blade 21 is shifted across the fixed blade in the usual way.

45 The clipper construction forms no part of the present invention and is adverted to merely to make clear that the structure of the clipper includes a spring which biases the blade to one position. This spring action is taken advantage 50

of in releasably securing the clippers in their holders.

To place a clipper in a holder of the display rack the handles 23 and 24 of the clipper are grasped in the usual way and these handles are pulled toward each other slightly and held in such position. While so held the blades of the clipper are slid down into the holders, the side edges of the fixed blade 20 moving under the 10 overhanging lugs 16 and 17 and the side edges of the movable blade being disposed in between these lugs. With the clipper in position in its holder the handles are released so that the left hand edge of the movable blade, as viewed in 15 Figures 1, 3, and 4, moves over and presses against the adjacent lug 16. This forces the opposite edge of the lower blade firmly in under its lug 17 and frictionally secures the clipper in place. The clipper may be released by reversing 20 this action, that is, by grasping the handles of the clipper, pulling them toward each other, and then sliding the cutting head of the clipper up out of its holder.

It will be seen from the foregoing that the 25 clippers are displayed in an attractive, natural manner and that when the clippers are in place the holders are effectively concealed. It will be noted also that the display board has capacity for quite a number of clippers considering its 30 size, this being due to the row formation which permits the spread handles of the larger size clippers to straddle the cutter heads of the clippers in the adjacent row.

Another advantage is that a variety of sizes 35 or styles of clippers may be advantageously displayed on one board and at the same time.

While I have shown and described one construction in which the invention may be advantageously embodied, it is to be understood that the construction has been selected merely for the purpose of illustration or example and that various changes in the size, shape and arrangement of the parts may be made without departing from the spirit of the invention or the scope of the subjoined claims.

The invention claimed is:

1. A display rack for hand hair clippers comprising a holder including a bracket arm adapted to be secured to a board and having a portion extending outwardly therefrom at an angle, and a bracket having the center of its body portion mounted on the outer end of the bracket arm and adapted to provide a support against which the lower blade of the clipper flatly rests, said body portion having overhanging end portions adapted to coact with the side edges of the 20 blades of the clipper to releasably secure the clipper in position.

2. A display rack for a hand hair clipper comprising a holder consisting of a bracket arm adapted to be attached to a suitable support and having a portion extending outwardly therefrom at an angle, a bracket having a strip-like body portion extending transversely to the outer end of the angle portion of the arm and secured thereto intermediate its ends, said body portion being adapted to provide a rest against which the bottom blade of the clipper engages, and angular lugs at the ends of the body portion adapted to overhang the side edges of the blades of the clipper to hold the clipper in position.

JOHN OSTER.
